UNITED STATES PATENT OFFICE

100,265

DESIGN FOR A BURIAL CASKET

Juul R. Goggins, Minneapolis, Minn.

Application October 26, 1935, Serial No. 59,236

Term of patent 7 years

To all whom it may concern:

Be it known that I, Juul R. Goggins, a citizen of the United States of America, residing at Minneapolis, in the county of Hennepin and State of Minnesota, have invented a new, original, and ornamental Design for Burial Caskets, of which the following is a specification, reference being had to the accompanying drawing, forming part thereof.

The figure is a perspective view of a burial casket, showing my new design.

The appearance of the open section of the cover when in closed position is the same as that of the complementary section of the top portion of the casket shown in closed position.

I claim:

The ornamental design for a burial casket, as shown and described.

In testimony whereof I hereunto affix my signature.

JUUL R. GOOGINS.
